UNITED STATES PATENT OFFICE.

CHARLES E. HEYER, OF CHICAGO, ILLINOIS, ASSIGNOR TO BARNHART BROS. & SPINDLER, OF SAME PLACE.

DESIGN FOR A FONT OF PRINTING-TYPE.

SPECIFICATION forming part of Design No. 18,603, dated September 11, 1888.

Application filed August 4, 1888. Serial No. 281,996. Term of patent 14 years.

To all whom it may concern:

Be it known that I, CHARLES E. HEYER, a citizen of the United States, residing at Chicago, county of Cook, and State of Illinois, have invented and produced a new and original Design for a Font of Printing-Type, which is set forth in the following specification, reference being had to the accompanying typographical impressions, which are exact representations of said design.

This design comprises upper and lower case letters, figures, points, dollar-mark, and character &. In general character it is rustic, of irregular outlines, and somewhat ornamental, tending toward grotesque. All lines are heavy and approximately uniform in width. Ceriphs are ununiform in slope and in the angle which they sustain to the principal line; but in no case are they horizontal. Whenever two ceriphs are applied at the same end of a single letter, the slope of said ceriphs is made different, and in most cases opposite. An effect aimed at in this design is to produce the appearance of a stagger by the irregularity of the lines of some of the letters, as the vertical strokes of capitals E, F, and L, which are curved toward the right. The lower horizontal line of capital E, the lower part of the curve of capitals C and G, and the lower horizontal line of capital L are made irregularly sinuous with the same effect. The capital R does not quite reach the line, whereby the letter is made to appear in danger of falling. The final stroke of lower-case h, m, and n and of upper-case N is made oblique. The characteristic of lower-case r is trumpet-shaped. The tail of lower-case g is abbreviated. The cross-stroke of lower-case f is united with the top of the principal stroke by a pendent stroke. Figures 3 and 5 have their lower curve expanded, so that the end of the

curve extends below the line, and the upper part of figure 5 is made to lean toward the right, making both of the lines oblique. The lower end of both upper and lower case Y and y is provided with a spur projecting to the right, 45 deviating slightly from a horizontal direction. Capitals C and G have their characteristic at the upper end in the form of an obliquely-situated wedge-shaped addition with the point downward, and making the junction with the 50 principal lines. Capital K has its two oblique lines inclined at slightly-unequal angles to the vertical line, and both said oblique lines are slightly bent, and the lower one does not extend quite so far down as the lower end of the 55 straight stem, the effect of all said irregularities being to give the appearance of instability to the letter.

I claim—

The design for a font of type herein shown 60 and illustrated, having lower-case letters, capitals, figures, and points comprised on heavy lines of uniform width, with sharp pointed ceriphs irregularly inclined with respect to principal lines, and having lower horizontal 65 lines of some capitals, as E, and the lower part of some curves, as of capitals C and G, irregularly sinuous, and having the lower end of the letter Y provided with a spur projecting to the right, capitals C and G having the wedge-shaped characteristic at the upper end located in an oblique position, pointing downward and to the left, substantially as set forth.

In testimony whereof I have hereunto set my hand, in the presence of two witnesses, at Chicago, this 2d day of August, A. D. 1888.

CHAS. E. HEYER.

Witnesses:

E. F. BURTON,
JEAN ELLIOTT.
